F. W. LANOIX.
CRUDE OIL BURNER.
APPLICATION FILED MAY 24, 1909.

950,450.

Patented Feb. 22, 1910.

Inventor,
Frederick W. Lanoix,
By F. G. Fischer,
Atty.

UNITED STATES PATENT OFFICE

FREDERICK W. LANOIX, OF KANSAS CITY, MISSOURI, ASSIGNOR TO A. W. FARNEY, OF KANSAS CITY, MISSOURI.

CRUDE-OIL BURNER.

950,450.

Specification of Letters Patent. Patented Feb. 22, 1910.

Application filed May 24, 1909. Serial No. 497,837.

To all whom it may concern:

Be it known that I, FREDERICK W. LANOIX, a citizen of the United States, residing at Kansas City, in the county of Jackson and 5 State of Missouri, have invented certain new and useful Improvements in Crude-Oil Burners, of which the following is a specification:

10 My invention relates to improvements in crude-oil burners, and one of my objects is to provide a simple and efficient burner of this character.

With the above and other objects in view, the invention may be said to consist in the 15 novel construction, combination, and arrangement of parts hereinafter described, illustrated in the accompanying drawing, and pointed out in the claims appended hereto, it being understood that various 20 changes in form, proportions, and minor details of construction may be resorted to without departing from the principle or sacrificing any of the advantages of the invention.

25 Referring now to said drawing: Figure 1 represents a vertical central section of the burner on line I—I of Fig. 2. Fig. 2 is a horizontal section on line II—II of Fig. 1. Fig. 3 is a broken, inverted plan view. Fig. 30 4 is an inverted perspective view of a disk employed in carrying out the invention.

In carrying out the invention, I employ 35 a hollow cup-shaped casting 1, comprising an inner wall 2 and an outer wall 3, spaced apart to form an air-chamber 4. The bottom portion of the outer wall 3 has a central opening 5 forming an inlet to chamber 4, and the upper portion of the inner wall 2 has an annular row of holes 6 forming an outlet from said air-chamber. The bottom portion of the inner wall 2 has a central depending nipple 7 threaded so that it may be connected to a supply-pipe, not shown.

40 45 8 designates a reinforcing member which is screwed upon the nipple to secure the same and the bottom of the outer wall together.

9 designates a sheet-metal pan fitting 50 within the inner wall from which it is spaced to form a second air-chamber 10, having communication with the air-chamber 4 through the holes 6. Pan 9 is provided at its upper end with an annular 55 flange 11 which rests upon the upper sur-

face of the outer wall, and said pan is held centrally within the inner wall 2 by a plurality of spacing lugs 12 integral with the upper portion of said inner wall. Pan 9 has a central opening 13 in its bottom portion to form an outlet for air-chamber 10, and through which oil in the bottom of the inner wall may be ignited. 60

14 designates a disk provided at its underside with lugs 15 which rest upon the bottom of pan 9, and have shoulders 16 for engaging the edge of opening 13 to hold the disk centrally within the pan. Disk 14 has a central opening 17 which registers with opening 13 so that the oil in the bottom 70 of the inner wall may be ignited. Said disk also overlaps opening 13 for a considerable distance to cause the flame to impinge against the bottom and side of the pan.

In practice oil is admitted to the bottom 75 of the inner wall 2 and ignited. The flame thus produced passes upward through openings 13, where it is spread against the interior of the pan by the disk 14. This heats the air in the chambers 4 and 10 and causes 80 it to flow outward through opening 13 and draw in a fresh supply through inlet 5. As the heated air escapes through opening 13 it becomes thoroughly intermixed with the flame, supplying the same with sufficiently 85 heated oxygen to insure complete combustion of the fuel. A small portion of the flame will also escape through opening 17 but as the same is small, compared to the annular opening 18 between the pan and 90 the edge of the disk, the greater portion of the flame will escape through said annular opening, and in impinging against the pan superheat the air in chamber 10.

Having thus described my invention, what 95 I claim is:

1. An oil burner consisting of a hollow cup-shaped casting comprising an outer wall and an inner wall forming an air-chamber with inlet and outlet openings in said walls, 100 oil-supplying means communicating with the bottom of the inner wall, a pan fitting within the inner wall and spaced therefrom to form a second air-chamber having an outlet through the bottom of the pan and communicating with the first-mentioned air-chamber through the outlet thereof, and a disk spaced above the bottom of the pan, substantially as described. 105

2. An oil burner consisting of a hollow 110

cup-shaped casting comprising an outer wall and an inner wall forming an air chamber with inlet and outlet openings in said walls, a nipple depending from the inner wall 5 through the inlet opening in the outer wall, reinforcing means engaging the nipple and the bottom of the outer wall, a pan removably fitting within the inner wall and spaced therefrom to form a second air-chamber 10 having an outlet through the bottom of the pan and communicating with the first-mentioned air-chamber through the outlet thereof, an annular flange carrying said pan and supported by the upper portion of the cup-

shaped casting, means extending inwardly 15 from the inner wall for holding the pan in proper relation thereto, and a disk spaced above the bottom of the pan and provided with a central opening registering with the opening in the bottom of the pan, said disk 20 being provided with lugs whereby it is supported above the bottom of the pan.

In testimony whereof I affix my signature, in the presence of two witnesses.

FREDERICK W. LANGIX.
